PULVERIZED FUEL BURNER

Aubrey J. Grindle, Chicago, Ill.

Application September 17, 1938, Serial No. 230,478

4 Claims. (Cl. 110—28)

The invention relates to pulverized fuel burners, and more particularly to burners of this character suitable for use in domestic or other small heating systems.

A general object of the invention is to provide an improved pulverized fuel burner of the above general character which, by reason of its simple, sturdy construction, relatively low cost, and efficient and reliable operation, is particularly suitable for use in domestic heating systems.

Another object is to provide a pulverized fuel burner embodying a nozzle of improved construction adapted to promote rapid ignition and complete combustion of the pulverized fuel.

Another object is to provide improved means for introducing secondary air into the burner to insure complete and intimate mixture of the fuel and air.

Another object is to provide an improved igniter for pulverized fuel burners which can be installed with a minimum of labor and which can be quickly and easily removed and replaced when necessary.

It is also an object of the invention to provide a novel method of burning finely pulverized fuel which enables this type of fuel to be utilized in domestic heating systems.

Other objects and advantages of the invention will become apparent from the following detailed description of the preferred embodiment illustrated in the accompanying drawing, in which:

Figure 1 is a central vertical sectional view of a pulverized fuel burner embodying the features of the invention.

Fig. 2 is a fragmentary plan view of the burner.

Fig. 3 is a sectional view taken along the line 3—3 of Fig. 1 showing the relationship of the fuel and secondary air orifices.

Fig. 4 is a sectional view taken along the line 4—4 of Fig. 1 showing details of the igniter.

By way of illustration, the invention has been shown and will hereinafter be described in connection with a steam or hot water heating plant of the type commonly used for domestic heating. It is to be understood, however, that the invention is not limited to the particular form or environment shown and that various modifications, adaptations and alternative constructions may be resorted to without departing from the spirit and scope of the invention as expressed in the appended claims.

Referring to the drawing, the burner constituting the exemplary embodiment of the invention is shown in connection with a steam or hot water heater having a boiler 5 with an inner

shell 6 defining a vertical, conically tapered combustion chamber 7. The combustion chamber is provided with a refractory lining 8. A combustion ring 9 of refractory material forms the upper wall of the combustion chamber and the lower wall of an air chamber 10 from which secondary air is supplied for the combustion of the fuel within the chamber 7.

The air chamber 10 is closed at its upper end 10 by a casing 11 having a removable top or cover 12. The casing 11 is generally V-shaped in horizontal cross section and rounded at its larger end (see Fig. 2) to fit tightly upon the upper end of the boiler shell 6. The smaller end of 15 the casing projects laterally over the top of the boiler to receive a secondary air duct 13 through which air under low pressure is supplied by a suitable blower (not shown). The connection between the duct 13 and the casing 11 is made 20 by way of a branch duct 14, leaving the end of the duct 13 open to provide a relief outlet for gases and thus prevent building up of excessive back pressures in the blower system due to puffs or small explosions which may occur in the combustion chamber when the burner is initially 25 started. The open end of the duct is closed by a relief door 15 hinged to a collar 16 encircling the duct. The weight of the door is sufficient to maintain the relief outlet closed under normal 30 operating conditions.

The various elements of the burner structure are assembled in a compact unit and mounted within the secondary air chamber 10. As shown in Fig. 1, the burner comprises a pulverized fuel nozzle 21 arranged to discharge downwardly into the combustion chamber 7 through the opening in the combustion ring 9. The nozzle in its preferred form consists of a generally conical hollow casting the walls of which taper gradually to a point approximately midway of its length and then flare outwardly as at 22 and merge into an enlarged cylindrical end portion 23. The outside diameter of the end portion 23 is such as to leave an annular opening communicating 40 between the combustion chamber 7 and the secondary air chamber 10. This opening constitutes the orifice through which secondary air is supplied for combustion of the fuel discharged through the nozzle.

The nozzle 21 is preferably supported from the cover plate 12 so as to avoid placing unnecessary strains on the combustion ring and the refractory lining of the combustion chamber. To this end, the nozzle is formed at its upper end with an annular flange 25 adapted to

be bolted or otherwise secured to the cover plate in registration with an aperture 26 which forms a passage for a fuel feed pipe.

The fuel feed pipe, as herein shown, consists of a tapered elbow 27 having its enlarged end formed with an annular flange 28 adapted to be bolted to the flange 25 of the nozzle. The other end of the elbow is supported by upstanding posts 27a welded or otherwise anchored to the boiler shell. A pipe or flexible tube 29 connected to the other end of the elbow by a coupling 30 extends to a suitable fuel feed mechanism (not shown) adapted to supply a mixture of primary air and comminuted fuel under pressure to the fuel line.

To insure intimate mixing of the fuel and primary air within the nozzle, a stationary mixer is preferably installed between the elbow and nozzle. The mixer, as herein shown, comprises a metal plate 31 adapted to be clamped between the flanges 25 and 28 of the nozzle and elbow. The area of the plate 31 within the nozzle is formed with an outer row of inclined vanes 32 and an inner row of oppositely inclined vanes 33 which divide the air and fuel mixture into a series of oppositely moving streams and thus insure the proper mixture of the fuel and air.

The fuel and air mixture delivered to the nozzle is discharged into the combustion chamber 7 in a manner such as to facilitate rapid ignition and complete combustion of the fuel in the combustion chamber. To this end, a spreader 36 is supported in the enlarged lower end of the nozzle by means of a rod 37 anchored in a boss 38 formed integrally with the elbow 27. As herein shown, the spreader comprises a hollow sheet metal shell having a generally conical top 39 and a substantially cylindrical body portion 40. The shell which is preferably open at its lower end may be filled with a suitable refractory material 40a to protect the metal parts from the heat of the combustion chamber.

The body portion 40 of the spreader is of substantially less diameter than the cylindrical lower wall 23 of the nozzle. When the spreader is centered in the nozzle, as shown in Fig. 1, it thus defines with the wall 23 an annular fuel orifice 41 concentric with the secondary air orifice.

The particular form and relationship of the orifices is of extreme importance in obtaining complete combustion of the fuel and in effectually eliminating coking or the deposit of unburned or partially burned fuel on the walls of the combustion chamber. The secondary air enters the combustion chamber in a hollow cylindrical stream surrounding the hollow cylindrical fuel and air stream which is of relatively large diameter. Moreover, the fuel and air stream is defined by a relatively thin wall of primary air and entrained fuel particles so that the fuel particles are quickly heated to combustion temperature by radiation from the burner flame and from the combustion chamber walls. Since the fuel and primary air stream is closely encircled by the cylindrical secondary air stream, the fuel particles are quickly dispersed through the secondary air stream which supports combustion.

This novel method of introducing the pulverized fuel and air into the combustion chamber in thin walled, relatively large diameter concentric hollow cylindrical streams enables such fuel to be used satisfactorily in the relatively small combustion chambers available in domes-

tic heating plants. Relatively low pressures may be employed, thus producing a soft flame which has no tendency to erode the walls of the combustion chamber. Moreover, complete combustion takes place in the upper end of the combustion chamber close to the burner so that coking or the deposit of carbon on the walls or burner parts is effectually avoided.

Rapid mixing of the fuel particles with the secondary air stream is facilitated and stratification of the air is prevented by the provision of means for imparting a rotary motion to the secondary air stream. This means, as herein shown, comprises a series of vanes 45 formed on the inner surface of an annulus 46 disposed within the opening of the combustion ring 9. As will be seen by reference to Fig. 3, the vanes 45 are inclined at an angle to the axis of the air orifice and therefore deflect the various components of the air stream from a vertical path. The annulus is supported on the combustion ring by means of a flange 47. Laterally projecting flanges 48 on the nozzle 21 bear against the flange 47 and prevent displacement of the ring when the burner is in operation.

Ignition of the pulverized fuel is effected by means of an igniter which, as herein shown, includes a pilot tube 51 arranged to project a gas flame through the secondary air orifice and into the combustion chamber 7. The pilot tube 51 is removably mounted in a generally vertical bore 52 formed in a boss 53 integral with the side wall of the nozzle. The bore 52 is preferably of generally oval cross section, thereby providing an air inlet for the pilot flame in addition to accommodating the pilot tube itself. As herein shown, the pilot tube 51 is supported in the bore 52 by means of laterally projecting lugs 54 engaging in longitudinally extending grooves 55 formed in opposite walls of the bore. Thus, the pilot tube may be readily assembled with the burner or removed for replacement or repair. A flexible pipe or tube 55 connected with the upper end of the pilot tube by means of a coupling 56 supplies gas to the pilot burner.

Ignition of the pilot burner may be effected in any suitable manner as by a hot wire igniter 57 of usual and well known construction. The igniter 57, as herein shown, is in the form of a tight coil of resistance wire mounted in a suitable holder 58 slightly below the lower end of the pilot tube 51. A shield 59 secured to the boss 53 and extending downwardly to the vane supporting flange 47 prevents the pilot flame from being extinguished by eddies in the secondary air chamber.

It will be understood that any suitable system of controls may be employed for controlling the operation of the burner. Such controls are old and well known in the art and are therefore not shown in detail. In general, it may be stated that the controls are so arranged that the secondary air blower is started and current is supplied to the igniter 57 upon a call for heat from the burner. After a predetermined delay sufficient to allow the igniter to reach the desired temperature, a valve in the gas pipe 55 is opened. The gas flowing from the pilot tube over the heated coil is ignited and forms a pilot flame which is projected into the combustion chamber. Simultaneously with the opening of the gas valve, the fuel feed blower is started and fuel and air mixture is discharged through the fuel orifice 41. The pilot flame ignites the particles of fuel thereby establishing combustion in the burner. The pilot flame may be allowed to

burn until the combustion chamber heats up sufficiently to ignite the fuel, whereupon the pilot flame is extinguished.

It will be apparent from the foregoing that the invention provides a pulverized fuel burner of simple and sturdy construction which is efficient and reliable in operation and particularly suitable for use in domestic heating plants. The burner embodies a nozzle of novel and advantageous construction arranged to discharge a primary fuel and air mixture into the combustion chamber in the form of a hollow cylindrical stream encircled by a cylindrical stream of secondary air. By reason of the improved method of introducing the fuel and air streams into the combustion chamber, the fuel particles are quickly and intimately mixed in the air stream so that complete combustion takes place in the upper part of the burner. Moreover, the stream of fuel and air mixture presents a relatively large surface area so that the fuel particles are quickly heated to ignition.

I claim as my invention:

1. In a pulverized fuel burner for use in a vertical combustion chamber, a combustion ring having a circular opening supported at the top of the combustion chamber, a nozzle having one end disposed in said opening and coacting with said ring to define an annular orifice for discharging a hollow cylindrical stream of secondary air into the chamber, means cooperating with said nozzle to form an annular fuel orifice concentric with said air orifice for discharging a hollow cylindrical stream of primary air and entrained pulverized fuel into the combustion chamber, a metal ring supported on said combustion ring and encircling said air orifice, and a series of vanes formed around the inner edge of said metal ring, said vanes being inclined relative to the axis of the ring and disposed within said air orifice and operative to produce axial rotation of the secondary air stream relative to the stream of primary air and pulverized fuel discharged through the fuel orifice.

2. In a pulverized fuel burner for use in a vertical combustion chamber, a combustion ring having a circular opening supported at the top of the combustion chamber, a nozzle having one end disposed in said opening and coacting with said ring to define an annular orifice for discharging a hollow cylindrical stream of secondary air into the burner, means cooperating with said nozzle to form an annular fuel orifice concentric with said air orifice for discharging a hollow cylindrical stream of primary air and entrained

55

pulverized fuel into the combustion chamber, a metal ring supported on said combustion ring and encircling said air orifice, a series of vanes formed around the inner edge of said metal ring and positioned in said air orifice, said vanes being inclined relative to the axis of the orifice to impart a rotative movement to the secondary air stream, and means formed integrally with said nozzle for holding said metal ring in fixed position.

3. The combination with a pulverized fuel burner for use in a vertical combustion chamber, said burner having a secondary air chamber disposed above the combustion chamber and opening into the same and a fuel nozzle mounted in said air chamber with its discharge end positioned in the opening to define concentric air and fuel orifices for the discharge of fuel and air into the combustion chamber, of means for igniting the fuel including, a gas pilot tube, a bracket formed integrally with the nozzle having a bore of generally oval cross section, said bore having grooves formed in the opposite walls thereof and being adapted to receive the tube, and flanges on said tube cooperating with said grooves in said bore to removably hold the pilot tube at one side of the bore substantially parallel to the axis of the air orifice and in communication therewith, said bore forming at its other side a duct for supplying air to support the combustion of gas discharged from the pilot tube.

4. In a pulverized fuel burner for use in a vertical combustion chamber, the combination of a combustion ring having a circular opening located at the top of the combustion chamber, a metal annulus disposed in said opening and having an outwardly projecting circumferential flange seated on the combustion chamber, an elongated frusto-conical fuel nozzle having an annular orifice at its larger end and connected at its smaller end with a fuel feed line, means for supporting the smaller end of the nozzle above and substantially coaxially of the opening in the combustion ring with the larger end thereof disposed in said annulus to define therewith a second annular orifice concentric with the first orifice, and means for positioning said larger end of the nozzle with reference to said annulus including radially projecting flanges on the nozzle shaped to extend over said annulus and to cooperate with the flange thereof, said radial flanges additionally acting to hold the annulus against movement relative to the nozzle.

AUBREY J. GRINDLE.
